UNITED STATES PATENT OFFICE

114,624

DESIGN FOR A READING LAMP

Samuel Weldon Rosenthal, New York, N. Y.

Application March 7, 1939, Serial No. 83,400

Term of patent 7 years

To all whom it may concern:

Be it known that I, Samuel Weldon Rosenthal, a citizen of the United States, residing at New York, in the county of New York and State of New York, have invented a new, original, and ornamental Design for a Reading Lamp, of which the following is a specification, reference being had to the accompanying drawing, forming part thereof.

In the drawing

Fig. 1 is a front elevational view of the reading lamp showing my new design;

Fig. 2 is a rear elevational view;

Fig. 3 is a side elevational view;

Fig. 4 is a top plan view thereof.

I claim:

The ornamental design for a reading lamp, as shown.

SAMUEL WELDON ROSENTHAL.
